UNITED STATES PATENT OFFICE.

JESSE DITSON, OF LITTLETON, COLORADO, ASSIGNOR TO THE J. GEO. LEYNER ENGINEERING WORKS COMPANY, OF LITTLETON, COLORADO, A CORPORATION OF COLORADO.

OIL-BURNER.

1,154,101.

Specification of Letters Patent. Patented Sept. 21, 1915.

Application filed January 13, 1913. Serial No. 741,668.

To all whom it may concern:

Be it known that I, JESSE DITSON, a citizen of the United States, residing at Littleton, in the county of Arapahoe and State of Colorado, have invented a certain new and useful Improvement in Oil-Burners, of which the following is a specification.

This invention relates to burners for oil and similar fluid fuel and has for its object the construction of a burner of this type in which the consumption of compressed air will be reduced and the atomization and combustion of the oil carried out with great efficiency.

With this object in view I have devised a burner, a practical embodiment of which is shown in the accompanying drawing, which shows a longitudinal section through the burner, partly in elevation.

The burner as shown comprises a discharge nozzle 1 the walls of which diverge for a considerable portion of its length, toward the point of discharge. The back end of the discharge nozzle 1 is adjustably threaded into a compressed air chamber casting 2 of generally spherical conformation, into the lower side of which is secured a compressed air supply pipe 3 which is controlled by a valve 4. Secured in the wall of the chamber 2 opposite the discharge nozzle 1 is an atmospheric air inlet pipe 5 the forward portion of which 6 passes through the chamber 2 and projects slightly into the back end of the discharge nozzle 1. The

edge of the opening in the back end of the discharge nozzle 1 is beveled outwardly and the forward part of the pipe 5 has a similar bevel on its outer surface. These two beveled surfaces are slightly separated, the amount of separation being determined by adjusting the threaded nozzle 1, the result being an inclined annular orifice 7 of variable width through which compressed air is directed from the chamber 2 into the discharge nozzle 1. The atmospheric air inlet pipe extends for some distance back of the chamber 2 and is provided on its lower side with an oil inlet opening 8 through which oil is supplied by a pipe 9 controlled by

valve 10. The rear end of the pipe 5 is normally open to the atmosphere through an aperture 11 but may be closed by a stop cock 12.

In operation when the valve 4 is opened compressed air will pass into the chamber 55 2 and through the orifice 7 into the discharge nozzle 1 passing out through the front end thereof with considerable force. When the stop cock 12 is open the passage of the compressed air through the nozzle 1 will draw 60 or entrain a considerable volume of atmospheric air through the pipe 5 and carry it through the nozzle 1. When the oil valve 10 is opened oil will pass into the tube 5 through the opening 8 and be partially atomized and 65 carried along through the pipe 5 by the current of air passing therethrough. When it reaches the forward end of the pipe 5 the compressed air flowing through the orifice 7 will still further atomize it so that it will 70 be thoroughly mixed with air and ready for complete combustion at the discharge end of the nozzle 1. By this construction therefore a large quantity of atmospheric air will be utilized in promoting combustion and by the 75 successive atomization and mixture of the oil with the atmospheric air and then with the compressed air an intimate commingling of air and oil is obtained which causes practically complete combustion and hence a 80 high degree of efficiency.

It is to be understood that the present showing and description discloses only one specified modification of my invention and other forms and modifications are included 85 in the spirit and scope of the invention as expressed in the claim.

What I claim is:

In an oil burner, a casing having a chamber therein, a pipe for admitting compressed 90 air to said chamber, an air conveying pipe projecting into said chamber, the outer end of said pipe being open to the atmosphere, an oil inlet pipe leading into the lower side of said air conveying pipe, and a diverging 95 nozzle adjustably secured in said casing, the inner end of said nozzle being slightly separated from the inner end of said air conveying pipe.

In testimony whereof, I have hereunto set 100 my hand.

JESSE DITSON.
